UNITED STATES PATENT OFFICE.

CYRUS H. KIRKPATRICK, OF SUGAR GROVE, INDIANA.

IMPROVEMENT IN HAY-STACKING APPARATUS.

Specification forming part of Letters Patent No. 129,967, dated July 30, 1872.

Specification describing a new and useful Improvement in Hay-Stacking Apparatus, invented by CYRUS H. KIRKPATRICK, of Sugar Grove, in the county of Tippecanoe and State of Indiana.

Figure 1 is a side view of my improved hay-stacker. Fig. 2 is a horizontal section of the same taken through the line $x x$, Fig. 1.

Similar letters of reference indicate corresponding parts.

My invention has for its object to furnish an improved apparatus for stacking hay, simple in construction, strong, durable, not liable to get out of order, and more convenient in use and effective in operation than hay-stackers constructed in the ordinary manner; and it consists in the construction and arrangement of the various parts of the apparatus, as hereinafter more fully described.

A is the base or platform of the apparatus, which is designed to be staked or otherwise secured to the ground at the side of the stack, or of the place where the stack is to be built. B is a post, the lower end of which is firmly secured to the platform A, and to the upper end of which is pivoted a crane, C. To the lower end of the post B and to the platform A is attached a flanged socket, D, through which the post B passes, and which is designed to serve as a journal for the driving-wheel E, to which is attached the sweep F, to which the horse is attached, and a leading-pole, G, to which the horse's halter is tied. Upon the upper side of the rim of the wheel E are formed beveled teeth, which mesh into the teeth of the small bevel-gear wheel H, placed upon the shaft I, which passes through and is securely attached to the lower part of the post B. The gear-wheel H is connected with the shaft I by a tongue and groove or other means, so that when in gear with the driving-gear wheel E it may carry the shaft I with it in its revolution, and when out of gear with said wheel E the said shaft I may revolve loosely within it, allowing the fork to descend for another load, while the horse continues to advance. To the shaft I is attached, or upon it is formed, a drum, J, to which is attached one end of the rope K, which passes over the guide-pulleys L attached to the crane C, and to its other end is attached a fork, M, for raising the hay. To the end of the shaft I that projects at the other side of the post B is at-

tached a drum, N, to which is attached a cord, O, the other end of which is attached to the side of the crane C, and which passes through guide eyes or pulleys P attached to the post B and crane C, and so arranged that as the cord N is drawn upon the crane C may be swung around, bringing the loaded fork over the stack. The drum N should be made in two or more parts of different diameters, so that by adjusting the cord O to wind upon one or the other of said parts the crane may be turned quicker or slower, according to the height of the stack. The time at which the crane C is swung around may also be regulated by giving the cord O, when slack, one or more turns around the drum N, or throwing off one or more turns from said drum. The outer end of the hub of the gear-wheel H is grooved to receive the forked end of the bar Q, which is bent to pass around the gear-wheel H and drum J, and its inner end is pivoted to the lever R, the end of which is pivoted to the lower part of the post B, so that by operating the said lever the gear-wheel H may be thrown out of and into gear with the gear-wheel E. The lever R may be provided with a cord or cords extending to the pitcher, so that the pitcher, without moving from his place, can throw the gear-wheel H out of and into gear with the gear-wheel E.

Having thus described my invention, I claim as new and desire to secure by Letters Patent—

1. The arrangement in a hay-stacker of the gear-wheels E H, shaft I, drum J, and rope K, with respect to each other and the base A, post B, and crane C, to enable the fork to be raised and lowered while the horse advances continuously, substantially as herein shown and described.

2. The arrangement of the drum N and cord O, with respect to the shaft I, post B, and crane C, substantially as herein shown and described, and for the purpose set forth.

3. The arrangement of the bar Q and lever R, with respect to the gear-wheel H, shaft I, and post B, substantially as herein shown and described, and for the purpose set forth.

CYRUS H. KIRKPATRICK.
